Specification for Design.

Patented June 2, 1914.

Application filed April 6, 1914. Serial No. 830,066. Term of patent 7 years.

To all whom it may concern:

Be it known that we, GEORGE M. BEARDSLEE and IRA L. FRENCH, citizens of the United States, residing at Chicago, in the county of Cook and State of Illinois, have invented a new, original, and ornamental Design for Lighting-Fixtures, of which the following is a specification, reference being had to the accompanying drawing, forming part thereof.

In the drawing:—Figure 1 is a side elevation of our new design illustrating the same applied to a canopy or body shell of lighting fixtures. Fig. 2 is a plan view of the same. Fig. 3 is a side elevation of our new design illustrating the same applied to a shade holder.

We claim:—

The ornamental design for a lighting fixture, as shown.

GEORGE M. BEARDSLEE.
IRA L. FRENCH.
